INSULATOR SUPPORT FOR UTILITY POLES

John E. Breeden, Royston, Ga., assignor to Hopeman Brothers, Inc., New York, N.Y.

Filed Sept. 30, 1974, Ser. No. 510,589

Term of patent 14 years

Int. Cl. D8—08

U.S. Cl. D8—234

FIG. 1 is a front elevation of an insulator support for utility poles showing my new design;

FIG. 2 is a rear elevation thereof;

FIG. 3 is a left side elevation thereof;

FIG. 4 is a right side elevation thereof;

FIG. 5 is a top plan view thereof; and

FIG. 6 is a bottom plan view thereof.

The fragmentary broken line representation of a utility pole and the broken line representation of insulators in FIG. 1 are for purposes of illustration only.

I claim:

The ornamental design for an insulator support for utility poles, as shown and described.
